AIRPLANE

Henri J. Myser, Mount Vernon, Ill.

Application December 17, 1952, Serial No. 22,740

Term of patent 14 years

(Cl. D34—15)

To all whom it may concern:

Be it known that I, Henry J. Myser, a citizen of the United States, residing at Mount Vernon, Jefferson County, State of Illinois, have invented a new, original, and ornamental Design for an Airplane, of which the following is a specification, reference being had to the accompanying drawing, forming a part hereof.

Fig. 1 is a top plan view of an airplane, showing my new design;

Fig. 2 is a side elevational view thereof;

Fig. 3 is a bottom plan view thereof;

Fig. 4 is a vertical cross-sectional view thereof, taken along the line 4—4 in Fig. 1;

Fig. 5 is a vertical cross-sectional view thereof, taken along the line 5—5 in Fig. 1;

Fig. 6 is a fragmentary vertical cross-sectional view thereof, taken along the line 6—6 in Fig. 1; and

Fig. 7 is a fragmentary vertical cross-sectional view thereof, taken along the line 7—7 in Fig. 1. The dominant features of my new design are shown in solid lines in the drawing.

I claim:

The ornamental design for an airplane, substantially as shown and described.

HENRI J. MYSER.
